UNITED STATES PATENT OFFICE.

CHARLES E. MERRIFIELD, OF INDIANAPOLIS, INDIANA, ASSIGNOR TO
WILLIAM M. JOHNSTON, OF WILMOT, OHIO.

LATHING.

SPECIFICATION forming part of Letters Patent No. 334,603, dated January 19, 1886.

Application filed November 2, 1885. Serial No. 181,570. (No model.)

To all whom it may concern:

Be it known that I, CHARLES E. MERRIFIELD, a citizen of the United States, residing at Indianapolis, in the county of Marion and 5 State of Indiana, have invented certain new and useful Improvements in Lathing, of which the following is a specification.

The objects of my improvements are to provide a lathing which, while having all the 10 advantages of the so-called "combined wooden sheathing and lath," will be cheaper and can with less difficulty be manufactured than the same. I attain these objects by the device illustrated in the accompanying drawings, in which—

Figure 1 is a perspective view of my improved lathing and plastering when applied to the walls or ceilings of a frame house, and Fig. 2 a vertical cross-section through my 20 lathing. In Fig. 3 I show the strips between the lath made in two pieces, each having a groove cut on but one edge and having the other edge straight.

Similar letters refer to similar parts throughout the several views.

A A are narrow wooden strips of about one inch thickness or more or less. These strips have a groove, a, cut in their edges of sufficient width to receive an ordinary lath, 30 B, and a certain amount of mortar, the strips A A, the lath B B, and the grooves a a forming the face-grooves G to receive the key of the plastering.

The device is applied in the following manner: A strip, A, is horizontally nailed to the wall, then a lath, B, is set onto the upper groove a of the strip A, a second strip is put onto the lath with its groove fitting over the same, the strip is nailed to the wall, then a 40 lath is inserted again on top of the last strip, and so on. The laths B are resting with their backs against the straight vertical back wall of the grooves a, while the front wall of said grooves, cut rabbeted, as shown in Fig. 2, or 45 beveled or rectangular, as shown in Fig. 3, holds the lath in place, and at the same time forms a key for the plastering P. The strips A A being of about the thickness of the common sheathing, and being spaced close together with the lath fitting into the grooves a a, the benefits and advantages of a combined sheathing and lath are obtained at

much less cost than the articles now manufactured under that name; for in the combined sheathing and lath where wedge-shaped grooves are cut into the face of the boards in order to form a key for the plastering the material thus cut out of the boards is a perfect loss.

Waste strips can be used to form my strips A A, thus utilizing and making valuable what otherwise would be of little or no value. Further, to cut the key-grooves into the face of the sheathing-boards requires the use of expensive and complicated machinery, while 65 in my device the edge grooves can be cut into the strips A A by any ordinary flooring-machine, with but the small outlay necessary to adapt the bit to the shape of the groove wanted. This is an advantage of great importance, as it will insure the manufacture and use of my device wherever a flooring-machine is operated.

Having thus fully described my invention, what I claim, and desire to secure by Letters 75 Patent, is—

1. A lathing consisting of the common lath B B and the narrow strips A A, having grooves a a cut into their edges of such a shape as to receive and hold the lath B B and 80 to form a key for the plastering, substantially as described and specified.

2. In lathing, the combination of the common lath B B and the narrow strips A A, said strips A A having grooves a a cut in 85 their edges of sufficient size and such a shape as to receive the lath B B and enough mortar to form a firm key for the plastering, substantially as described and specified.

3. In lathing, the combination, with the 90 common lath B B, of the narrow strips A A, of sufficient thickness as to have grooves a a cut into their edge wide enough to receive the lath B B, and to allow of a mortar-key for the plastering between the face of the lath and the 95 front wall of the groove, substantially as described and specified.

In testimony whereof I have signed my name to this specification in the presence of two subscribing witnesses:

CHARLES E. MERRIFIELD.
